MACKNEELE COX, OF STOLLINGS, WEST VIRGINIA, ASSIGNOR OF ONE-HALF TO
H. M. McGHEE, OF STOLLINGS, WEST VIRGINIA.

CABLE HOOK.

Application filed March 24, 1925. Serial No. 18,669.

This invention relates to a cable hook, designed primarily for use in connection with mine car motors or mining machines with which it is customary to employ a reel, but it is to be understood that a cable hook, in accordance with this invention, can be employed for any purposes wherein it is found applicable, and the invention has for its object to provide, in a manner as hereinafter set forth, a yieldable cable hook of the fuse type, which is effectively insulated for the protection of the operator, overcomes the application of sudden jerks to the reel when starting the car or machine, under such conditions preventing injury to the reel, prevents sudden tension on the cable which otherwise would inflict injury to or perhaps the breakage thereof, and further preventing blow-outs. Further objects of the invention are to provide, in a manner as hereinafter set forth, a yieldable cable hook of the fuse type for protecting the gathering cable, reel and controller of electric motors and coal cutting machines, and which is simple in its construction and arrangement, strong, durable, compact, thoroughly efficient and convenient in its use, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a vertical sectional view of a cable hook, in accordance with this invention.

Figure 2 is a fragmentary view in vertical section, of the hook upon an enlarged scale.

Figure 3 is a section on line 3—3, Figure 2.

Figure 4 is a section on line 4—4, Figure 3.

Figure 5 is a section on line 5—5, Figure 3.

Figure 6 is a plan view, in section, illus-

trating the locking members for one end of the fuse in open position.

Figure 7 is a disassembled view of the co-relating parts providing a lock for one end of the fuse.

Figure 8 is a perspective view of a pair of locking members, in closed position.

Referring to the drawings in detail, a yieldable cable hook, in accordance with this invention, comprises a cylindrical outer casing of insulation consisting of a body portion 1 having an open top 2 and a bottom 3 formed with an opening 4. Integral with the bottom 3 is a hollow reduced extension 5, provided with a closed outer end 6 and with a pair of aligning flaring openings 7 in a pair of opposed sides thereof. The inner face of the extension 5 is flush with the wall of the opening 4, and said extension 5 is formed of the same material as the body portion 1.

Arranged within the outer casing, as well as extending above the open end of the body portion 1, is an inner cylindrical, sectional casing formed of non-conducting material. The inner casing is seated on the bottom 3 of the outer casing and consists of an upper section 8, a lower section 9 and intermediate sections 10, 11 and 12. The section 8, which extends above the outer casing, has the periphery of its extended portion threaded, as at 13, and the extended portion of the section 8 is open. The lower terminal portion of the section 8 is reduced in thickness, as at 14, 15 and 16. The part 14 is provided with internal threads, the inner face of the part 15 is plane, and the inner face of the part 16 is threaded.

The upper terminal portion of the section 11 is reduced in thickness, as indicated at 17, thereby providing an internal shoulder 18, which constitutes a seat. The lower terminal portion of the section 11 is reduced in thickness, as indicated at 19, thereby providing an internal shoulder 20 which forms a seat. The section 10 has the upper part of its periphery threaded and the lower part plane. The threaded part of the section 10 extends into the lower end of the section 8 and threadedly engages with the reduced part 16 of said section 8. The lower part of the section 10 extends into the reduced upper terminal portion of the section 11 and is mounted on the seat 18. The lower part of the section 10 is secured to the reduced part

17 of the section 11 by the hold-fast devices 21.

The section 9 has its lower end formed with an inwardly extending annular flange 22, which seats on the bottom 3 of the outer casing, and the inner face of the section 9 is threaded. The upper end of the section 9 abuts against the lower end of the section 11. The section 12 has the upper part of its periphery plane and the lower part thereof threaded. The section 12 extends into the lower end of the section 11 and abuts against the shoulder 20, and further is connected to the lower end of the section 11 by the hold-
fast devices 21. The section 12 extends into the section 9 and threadedly engages therewith.

The upper end of the outer casing and section 8 of the inner casing are closed by a cap 24 of insulation, which threadedly engages with the threads 13 and abuts against the top edge of the outer casing. The cap 24 is formed with a centrally disposed opening 25.

Arranged within the casing and threadedly engaging with the part 14 of the section 8 is a contact block 26, formed with a diametrically extending groove 27 in its upper face and provided on its lower face with a depending contact rib 28.

Arranged within the sections 10, 11 and 12 of the inner casing, is a laminated fuse 29 and each lamination thereof is of like construction and is formed with an inclined intermediate portion 30, an upper end portion 31 and a lower end portion 32, and the inclined intermediate portion offsets the upper end portion 31 with respect to the lower end portion 32, so that the upper end portion 31 will extend in a plane parallel to the plane of the lower end portion 32. The upper end portion of the fuse 29 is arranged in the section 10 and the lower end portion in the section 12.

Associated with each end portion of the fuse 29 is a conducting head and each of which consists of a disk 33, having one face provided with an apertured lug 34 and its other face with a reduced neck 35. The heads are oppositely disposed with respect to each other, and the lug 34 of one of the heads is connected to the upper end portion 31 of the fuse by a hold-fast device 36, and the lug 34 of the other head is connected to the lower end portion 32 of the fuse by the hold-fast device 37. That head which is connected to the end portion 31 of the fuse 29, has formed integral with the neck 35 thereof a cylindrical contact 38 of less diameter than the disk 33 of such head. That head, which is connected to the lower end 32 of the fuse 29, has depending from the neck 35 thereof a combined contact and coupling member 39 of greater length than the contact 38. The member 39 extends through

the flange 22, opening 4 and completely fills the extension 5. The member 39 is formed with a passage 40, which registers with the opening 7 formed in the extension 5. The disk 33 of each of said heads is of less diameter than the sections 10 and 12, and the disk of the upper head is positioned within the upper end of the section 10 and the disk of the lower head is positioned within the lower end of the section 12.

The upper head is locked to the section 10 and the lower head to the section 12. The upper end of the section 10 is provided with a pair of diametrically opposed notches 41, and the lower end of the section 12 is formed with a pair of diametrically opposed notches 42. The notches 41 and 42 cooperate with the locking devices for the heads of the fuse. As each of the locking devices is of the same construction, but one will be described, as the description of one will apply to the other.

Each locking device comprises a collar 43 adapted to surround the contact 38 or the member 39. The collar 43 is formed with diametrically opposed sockets 44, in which are seated pivots 45, each extended from one end of an arcuate-shaped locking member 46. Each of said members 46 is formed with a locking pin 47, intermediate its ends, and on that face opposite the face from which projects the pivot 45. The outer edge of each locking member is notched as at 48, to facilitate the opening movement of said members. The locking pins 47 of each pair of members 46 coact with a pair of notches 41 or 42 for maintaining the fuse head in locked position. Each pair of locking members surrounds a neck 35 of a fuse head. The locking members 46 of each pair project beyond the edge of the disk 33 when the locking members are in closed position, see Figures 4 and 5, and when in open position are swung outwardly on the collar 43, see Figure 6.

Extending through the opening 25 is a hook element consisting of a substantially elongated shank 49, provided at its outer end with a hook 50 and at its inner end with a tapered contact head 51 which engages in the groove 27 of the contact 26. The shank 49, intermediate its ends, carries a sliding collar 52. That portion of the shank 49, within the inner casing, carries a pair of controlling springs 53, 54. The former is interposed between the collar 52 and the cap 24, and the latter between the collar 52 and the contact head 51. The springs 53, 54, collar 52, cap 24 and contacting head 51 provide a resilient or yieldable coupling or cushion between the hook element and the cable 55, which is attached to the member 39 and extension 6, when the hook element is connected to the conductor 56 and it is this resilient or yieldable coupling or cushion which overcomes

sudden jars on the reel. The cable 55 is extended through the passage 40 and openings 7 and secured together as at 57 to provide a loop connection 58 with the outer casing and member 39.

The hook 50 is so formed as to enable it to be quickly connected to and removed from the conductor 56 when desired, and for such purpose the back of the hook, as well as the 10 bill thereof is disposed at opposite inclinations.

The outer casing and cap 24 being formed of insulation material throughout act to effectively protect the operator when gripping 15 the outer casing to connect with the conductor 56. The length of the outer casing is to be materially greater than the width of the hand of the operator. The cable 55 electrically connects with the member 39, but 20 if the cable 57 is of the insulated type, a portion of its length is bared so that contact can be had with the member 39.

It is thought that the many advantages of a yieldable cable hook of the fuse type, in 25 accordance with this invention, can be readily understood, and although the preferred embodiment of the invention is as illustrated and described, yet it is to be understood that changes in the details of construction can 30 be had which will fall within the scope of the invention as claimed.

What I claim is:—

1. A cable hook for the purpose set forth comprising an outer casing of insulation, an 35 inner casing formed of a series of interengaging sections, a fuse arranged within the lower portion of said inner casing and including an upper and a lower conducting head, said lower head extending into said 40 outer casing, a yieldable hook element extending into said inner casing and provided at its inner end with a contact head, a contact block within and threadedly engaging with the sectional casing and interposed between the head of said element and said upper 45 conducting head, said lower conducting head and outer casing having registering means for coupling a cable therewith.

2. A cable hook for the purpose set forth 50 comprising an outer casing of insulation, an inner casing formed of a series of interengaging sections, a fuse arranged within the lower portion of said inner casing and including an upper and a lower conducting 55 head, said lower head extending into said outer casing, a yieldable hook element extending into said inner casing and provided at its inner end with a contact head, a contact block within and threadedly engaging with the sectional casing and interposed between the head of said element and said upper 60 conducting head, said lower conducting head and outer casing having registering means for coupling a cable therewith, and a releasable locking device for each of said 65

conducting heads, said devices when in locking position engaging with said inner casing.

3. A cable hook for the purpose set forth comprising an outer casing of insulation, an inner casing formed of a series of interengaging sections, a fuse element arranged within the inner casing and extending into the outer casing, means engaging with the inner casing for detachably locking the fuse element therein, a contact block arranged 70 within and threadedly engaging with the sectional casing and electrically engaging with the upper end of the fuse element, a hook element extending into said inner casing, cushioning means carried by the hook element, said cushioning means maintaining the fuse element in electrical contact with said contact block, and said outer casing and fuse element having registering means for 75 coupling a cable therewith.

4. A cable hook for the purpose set forth comprising an inner and an outer casing, said inner section formed of a series of interengaging sections, said outer casing formed throughout of insulation, a fuse element arranged within the sectional casing and provided with a contact member extending into the lower end of the outer casing, a contact block arranged within and secured to the inner face of the sectional casing and 80 electrically contacting with said fuse element, a hook element extending into said inner casing and provided at its inner end within the casing with a contact head engaging said block, cushioning means carried by said hook element, and said outer casing and contact member having registering means for 85 coupling a cable therewith.

5. A cable hook for the purpose set forth comprising an inner and an outer casing, 100 said inner section formed of a series of interengaging sections, said outer casing formed throughout of insulation, a fuse element arranged within the sectional casing and provided with a contact member extending into the lower end of the outer casing, a contact block arranged within and secured to the inner face of the sectional casing and 105 electrically contacting with said fuse element, a hook element extending into said inner casing and provided at its inner end within the casing with a contact head engaging said block, cushioning means carried by 110 said hook element, said outer casing and contact member having registering means for coupling a cable therewith, and means engaging with each end of the fuse element and further engaging in the outer ends of a pair of sections of the inner casing for detachably locking the fuse element in said 115 casing.

6. A cable hook for the purpose set forth comprising an outer casing of insulation, an inner casing of non-conducting material extended from the upper end of the outer 130

- casing, a fuse arranged within the lower portion of said inner casing and including a pair of conducting heads, one of said heads provided with a contact member extended from the inner casing into the outer casing and the other of said heads provided with a contact positioned within the inner casing, a contact block arranged within the inner casing and engaging said contact, a hook element extending into said inner casing and provided at its inner end within the casing with a contact head engaging said block, cushioning means carried by said element, and means engaging with the extended part of said inner casing and surrounding said element for confining said cushioning means and for closing said outer casing, said outer casing and contact member having registering means for coupling a cable therewith.
- 15 7. A cable hook for the purpose set forth comprising an outer casing of insulation, an inner casing of non-conducting material extended from the upper end of the outer casing, a fuse arranged within the lower portion of said inner casing and including a pair of conducting heads, one of said heads provided with a contact member extended from the inner casing into the outer casing and the other of said heads provided with a contact positioned within the inner casing, a contact block arranged within the inner casing and engaging said contact, a hook element extending into said inner casing and provided with a contact head engaging said block, cushioning means carried by said element, means engaging with the extended part of said inner casing and surrounding
- 20 said element for confining said cushioning means and for closing said outer casing, said outer casing and contact member having 40 registering means for coupling a cable therewith, and means mounted on said conducting heads and engaging into the inner casing for detachably locking said fuse to said casing.
- 25 8. A cable hook for the purpose set forth comprising a laminated fuse body provided at each end with a conducting head, a sectional casing for said fuse body, releasable locking devices for said heads interengaging 50 with a pair of sections of said casing, a spring controlled conducting element extending into said casing, electrically connected with one of said heads and formed with a hook at its outer end, and said other head having means for connecting a cable therewith exteriorly of said casing, the controlling spring for said element arranged 55 within said casing.
- 30 9. A device for the purpose set forth comprising an insulated casing, a laminated fuse body mounted therein and provided at each end with a conducting head, a spring controlled conducting element extending into 60 said casing, electrically connected with one of said heads and formed with a hook at its outer end, and said other head having means for connecting a cable therewith exteriorly of said casing, the controlling spring for said element arranged within said casing.
- 35 In testimony whereof, I affix my signature hereto.

MACKNEELE COX.
